UNITED STATES PATENT OFFICE.

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH OR SOCKET KEY.

2,282,365.

Specification of Letters Patent. Patented Oct. 22, 1918.

Application filed January 22, 1917. Serial No. 143,881.

To all whom it may concern:

Be it known that I, Frederic P. Gates, a citizen of the United States of America, and residing at Hartford, in the county of Hartford and State of Connecticut, have invented a certain new and Improved Electric Switch or Socket Key, of which the following is a specification.

My invention relates to keys for electric sockets or switches and particularly to keys of the type having a molded thumb piece attached to a metal shank. The object of my invention is to provide a key having a shank of special form struck from sheet metal and formed to shape.

In the accompanying drawings.

Figure 1 is a plan of a key in which my invention is embodied in one form;

Fig. 2 is a cross section on the line 2—2, Fig. 1;

Fig. 3 is a cross section on the line 3—3, Fig. 2; and

Fig. 4 is a plan of the sheet metal blank.

The common practice in the manufacture of socket keys is to hold an insulating thumb piece upon the end of a piece of cylindrical wire, the end at which the thumb piece is secured being in some instances given a particular shape in order to better secure it to the thumb piece. This involves generally a cutting or splitting of the wire and subsequent bending operation, which add materially to the cost of manufacture without affording equivalent improvement in construction.

The construction which I have adopted, while extremely simple and economical to manufacture, affords a secure anchorage for the thumb piece which effectually prevents any tendency to swivel, reinforces the thumb piece and facilitates and improves the key construction to a marked degree.

As here illustrated the key shank is struck from a piece of sheet metal and, as indicated in Fig. 4, comprises a flat shank 10 having a flat broad head 11 lying in the plane of the shank and centrally apertured at 12. An enlargement 13 is provided at the opposite end of the shank, and an intermediate shoulder 14. The enlarged end 13 of the shank may be subjected to the action of swaging dies to form the extreme end into a cylindrical bearing 15 for the key, leaving the adjacent enlarged section in the form of wings 16 which engage the switch piece (not shown)

in well understood fashion. The shoulder 14 forms a positioning member which holds the key in proper position within the socket in the manner now commonly accomplished by a washer. The insulating thumb piece 17 is molded upon the enlarged head 11 and the molded material not only surrounds the head but penetrates the hole 12 therein thus obtaining a secure anchorage. The head 11 affords wings which support the thumb piece 17 at all points and the latter is not as subject to fracture as in the ordinary thumb piece. It has been found to be a decided advantage in the molding operation to have the shank 10 flat, since it assures the location of the head 11 in the mold with accuracy in the mid plane of the thumb piece. I do not limit my invention to the precise form of the mandrel or the precise shape of the insulating thumb piece formed thereon, which may be variously modified without departing from what I claim as my invention.

I claim as my invention:

1. A key of the type described comprising a flat sheet metal shank of generally rectangular cross section having at one end wings lying in the plane of the shank and extending on opposite sides of its axis, together with a flattened thumb piece of insulating material molded on said enlarged head and confining the latter in its mid plane.

2. A key of the type described comprising a flat sheet metal shank of generally rectangular cross section having at one end wings lying in the plane of the shank and extending on opposite sides of its axis, together with a flattened thumb piece of insulating material molded on said enlarged head and confining the latter in its mid plane, a portion of the shank being shaped into a cylindrical bearing for the key.

3. A key of the type described comprising a flat sheet metal shank of generally rectangular cross section having at one end wings lying in the plane of the shank and extending on opposite sides of its axis, together with a flattened thumb piece of insulating material molded on said enlarged head and confining the latter in its mid plane, and lateral extensions on said shank for engaging a switch piece.

4. A key of the type described comprising a flat sheet metal shank of generally rectangular cross section having at one end

- wings lying in the plane of the shank and extending on opposite sides of its axis, together with a flattened thumb piece of insulating material molded on said enlarged head and confining the latter in its mid plane, a portion of the shank being shaped into a cylindrical bearing for the key, and lateral extensions adjacent said bearing to afford means for engaging a switch piece.
- 10 5. A key of the type described comprising a flat sheet metal shank of generally rectangular cross section having at one end wings lying in the plane of the shank and extending on opposite sides of its axis, together with a flattened thumb piece of insulating material molded on said enlarged

head and confining the latter in its mid plane, a portion of the shank being shaped into a cylindrical bearing for the key, and lateral extensions adjacent said bearing to afford means for engaging a switch piece, together with a positioning shoulder on the shank lying between said bearing and the thumb piece.

In testimony whereof I have signed my name to this specification, in the presence of two subscribing witnesses.

FREDERIC P. GATES.
